UNITED STATES PATENT OFFICE.

FRANK W. MONAGHAN, OF WATERTOWN, NEW YORK, ASSIGNOR TO THE BAGLEY AND SEWALL COMPANY, A CORPORATION OF NEW YORK.

PAPER-MAKING MACHINE.

Application filed January 20, 1921. Serial No. 438,602.

To all whom it may concern:

Be it known that I, FRANK W. MONAGHAN, a citizen of the United States, residing at Watertown, county of Jefferson, and State 5 of New York, have invented certain new and useful Improvements in Paper-Making Machines, fully described and represented in the following specification and the accompanying drawings, forming a part of the 10 same.

This invention relates to certain improvements in paper making machines, and has been designed particularly for use in that type of machine employing a wire, as the 15 Fourdrinier machine.

In the manufacture of paper on this type of machine, the stock which is to be made into paper is fed continuously to the wire section of the machine in the form of pulp 20 or stock mixed with a quantity of water. This pulp mixed with water is flowed on to the wire from a flow box past a slice and the web is formed on this making wire. This wire is as well known, a continuous wire 25 section of a suitable mesh which is given a travelling movement, and which passes during this movement over a series of rolls called table rolls and over suction boxes, the function of these rolls and suction boxes being to extract the water from the pulp on 30 the wire and to support the wire during the formation of the web or sheet. After the pulp on the wire has passed the suction boxes, it is formed into the sheet but is still 35 wet and weak. After the formed sheet leaves the wire, it is carried on a continuous felt band to and through a series of rolls known as press rolls which further remove free moisture from the sheet not taken out 40 at the suction boxes. At the point where the web or sheet leaves the wire there is a gap across which the web is led to the felt. Heretofore difficulty has been experienced in getting the web which is still wet to leave the 45 wire so that it will cross this gap to the felt. In constructions as heretofore used, furthermore, the web is drawn across the gap from the wire to the felt by the pull on the web.

As the web is still wet and weak and is felted into the wire the pull necessary to thus free 50 the web from the wire and carry it across the gap causes breaks in the web.

It is one object of the present invention to provide means whereby the web may be freed from its felting on the wire and removed therefrom throughout its width and 55 yieldingly supported on a layer or cushion of air from off which the web taking devices, such as felts, draw the web across the gap. The draw or pull necessary is thereby reduced and the consequent tendency of the 60 web to break between the wire and the web taking devices is greatly decreased.

With this and other objects not specifically referred to, the invention consists in certain 65 novel parts and combinations which will be fully described in connection with the accompanying drawings which show a preferred construction for effecting the object of the invention.

In these drawings:—

Figure 1 is an end elevation of so much of a Fourdrinier paper machine as is necessary for an understanding of the invention.

Figure 2 is a side view partly in section 75 and partly broken away of the construction shown in Fig. 1, looking in the direction of arrow 2 of that figure.

Figure 3 is a cross section through the couch roll and adjoining parts, the section 80 being taken on line 3—3 of Figs. 2 and 6.

Figure 4 is a sectional side view of the construction shown in Fig. 3 with the couch roll removed, the section being taken on line 4—4 of Fig. 3.

Figure 5 is a top plan view partly broken away of the construction shown in Fig. 4.

Figure 6 is a view similar to Fig. 4 on an enlarged scale, partly broken away with certain parts omitted.

Figure 7 is a detail sectional view on an enlarged scale, the section being taken on line 7—7 of Fig. 6.

Figure 8 is a detail sectional view, the section being taken on line 8—8 of Fig. 6.

Figure 9 is a detail sectional side view of

the valve plate and its co-operating valves for controlling the entrance of air.

Figure 10 is an end view of the construction shown in Fig. 9 looking to the right in that figure;

Figure 11 is a detail view of the valve plate.

Figure 12 is a detail edge view of the plate shown in Fig. 11.

10 Figure 13 is a detail view partly broken away of one of the valves shown in Fig. 9.

Figure 14 is an edge view of the same.

Figure 15 is a detail sectional view taken on line 15—15 of Fig. 4; and

15 Figure 16 is a perspective view of the main controlling valve plate.

Referring now to these drawings and first to Fig. 1, the continuous making wire is indicated by the letter W. This wire is

20 given a continuous travelling movement from the flow box and over table rolls and suction boxes (not illustrated) to the couch roll indicated by the numeral 1. This couch roll is driven in any suitable manner, as

25 from a gear 2 indicated in dotted lines in Fig. 1, and is supported in frames 3 on each side of the machine. The wire passes to this couch roll over a guide roll 4 around the couch roll and back over a carrying roll

30 5. Located adjacent the couch roll 1 is a driven paper roll 6 hereinafter referred to, under which the web of paper indicated at 7

35 is led to the web taking devices, shown as the felt 8. This felt is a continuous travelling band passing over a roll 9 to and between the press rolls, a pair of which are indicated at 10, and back to the roll 9 over felt roll 11.

The web of paper is drawn by the felt across the gap between the couch roll and

40 the felt to and between the press rolls. In accordance with the invention means are provided for freeing the web from the wire and yieldingly supporting it as it is separated so that the felt draws the web from

45 off this yielding surface and the strain necessary to pull the web away from the wires is lessened and breaks in the web are less liable to occur. In the preferred construction this separation is effected by producing a fluid

50 pressure under the web which, in addition to separating the web from the wire, forms a layer or cushion to yieldingly support the web as it leaves the wire, that is, a fluid

55 layer is formed under the web on which the freed web floats. This pressure fluid is preferably air and a layer of air is formed under the web from the top of which layer the web is drawn by the felt across the gap. This air

60 is supplied substantially evenly across the roll which is of considerable width, so that the sheet leaves the wire throughout its width.

The specific construction employed for

65 effecting this may be somewhat varied. A convenient one, however, and one which has

worked well in practice is that illustrated and which will be described.

In the machine selected to illustrate the invention, the couch roll is a suction roll, that is, suction means are provided co-oper-

70

ating with the roll to suck out additional water from the web not removed by the suc-

tion boxes. In the particular construction illustrated the roll has a perforated surface, the perforations being indicated by the

75

numerical 12. This roll rotates past a suction-chamber which is provided in a casting 13

spring-seated as indicated at 14 in the frames 3 of the machine before referred to, so as

to extend through the roll. This suction chamber is indicated at 15 and communicates

80

through a pipe 16 with any suitable suction apparatus not illustrated. Suction chamber

85

15 connects through ports 16' (see Fig. 4) with a chamber 17 which connects through

88

ports 18 with a chamber 19 formed by two spaced extensions 20, 21 rising from the cast-

13

before referred to. This chamber 19

14

communicates with the ports 12, and as the couch roll rotates over this chamber carrying

150

the wire with it, water is sucked through the ports 12 and into the chamber 19. Packing

155

22 is provided at the sides to form a close fit between the interior of the roll and the casting. In accordance with the invention

160

there is provided means for admitting a current of air under suitable pressure through this perforated couch roll, where

165

such construction is employed, so as to free the web from the wire throughout its width

170

after the roll carrying the web and wire has passed the suction chamber, and for yield-

175

ingly supporting the web at the point where it is freed from the wire. Various construc-

180

tions may be employed. Such constructions, however, will preferably include means

185

whereby a substantially even current of air may be distributed along the roll, and fur-

190

thermore will include means whereby the air delivered at any point of the roll may be

195

varied as desired, and the required adjust-

200

ments having been made, air may be ad-

205

mitted widthwise of the roll at different

210

points simultaneously. In the construction illustrated the interior of the casting 13 be-

215

fore referred to is partitioned off at one end by a partition 23 best shown in Fig. 7

220

and in dotted lines in Figs. 4 and 5 to form

225

a pressure chamber to which air under pres-

230

sure may be admitted through a pipe 24

235

from any suitable compressor apparatus not

240

illustrated. From this chamber lead a plu-

245

rality of passages 25, 26, 27, 28 and 29

250

formed in casting 30 secured by bolts 31 or

255

in any other suitable manner to that side of

260

the casting 13 before referred to away from

265

or after the suction chamber 19. While five

270

of these passages have been illustrated, it

275

will be understood that they and their con-

280

trolling valves hereinafter referred to will

be provided in such numbers as may be required. These passages connect through narrow ports 32, formed in an extension 33 of the casting 30, with the interior of the couch roll and closely adjacent one of the extensions 21 before referred to. On the opposite side of these ports the extension 30 is provided with an adjustable packing strip 300 reaching nearly to the interior surface

10 of the roll.

At each end of the chamber thus formed is provided a block or packing 301 which keeps the air from escaping endways.

The extension 21, the strip 300 and the 15 packing 301 thus form a chamber, which confines the air issuing from the ports 33 and directs the air out through the perforations 12 in the roll and acts to free the web from the wire at the desired point.

20 The admission of air to the passages 25-29 inclusive is controlled so that the amount of air supplied through any passage may be varied independently of the air supplied to any other, so that the expansion of the air as it passes lengthwise of the roll may be compensated for and the passages so adjusted that air under substantially similar pressure will be delivered from all the ports, so that the sheet will be 25 freed from the wire evenly throughout its width, and consequent breakage thereby prevented.

In the particular construction for effecting this object, there is provided what may 30 be termed a main gate valve 35 which slides in a groove 36 formed in the walls of the chamber casting 13 before referred to. This valve plate is connected by a rod 37 and a link 38 to a lever 39 pivoted at 40 to a 35 bracket 41 supported from the frame of the machine. The inner wall of the pressure chamber 30 is formed of a plate 42 secured to a wall of the casting 13 by screws 420. This plate 42 is a valve plate and is formed 40 with a succession of stepped seats 43. Each of these seats 43 extends beyond an adjacent seat so as to form with co-operating valve openings or ports 44 as clearly shown in 45 Figs. 9 and 11. Each of these seats is 50 formed as shown in Fig. 12 with a guide surface 45 cut to form grooves 46 which extend in under the seats 43 at each side. Co-operating with the valve plate 42 are a plurality of valves 47, 48, 49, 50 and 51, 55 one of these valves being provided to control one of the passages before referred to. These valves are in the form of slides having a grooved under-portion 52 which slides on the guides 45 before referred to and an 60 extension or leg 53 which slides into the groove 46 in the seats 43. These valves also dove-tail into each other, and to effect this the top of each of the valves 48 to 51 inclusive, that is, all of the valves below the 65 first one, are formed with a projection 54

shaped like the seat 45 before referred to, which slides in the groove of the valve. The valves can thus be interlocked, and escape of air therebetween, except from the ports, prevented. The ports 44 connect with each of the 70 passages 25 to 29 inclusive and by manipulating the slide valves the area of the ports can be adjusted so as to admit more or less air to each passage.

These slide valves may be adjusted in any 75 suitable manner. In the particular construction illustrated, each valve is provided (see Figs. 6, 7 and 10) with a projection 55 in which is secured by a screw 56 one end of a rod 57. The other end of these rods are 80 threaded, as indicated at 58, and pass through the end wall of the casting 30 and through a bracket 59. These rods have at one side of the bracket collars 60 and at the other side set-up nuts 61 by turning which 85 the screws and through them the slide valves may be adjusted to open and close ports 44 as desired.

When these valves have been adjusted to the air pressure which it is desired to 90 use for any particular weight of web, the main valve 35 is operated by lever 39 to open the ports 44 so that air may be simultaneously admitted from the pressure chamber through such ports as are opened 95 through the passages and along the roll.

The air under suitable pressure frees the web from the wire and forms a layer or cushion of air under the web, this layer or cushion being formed in part by the resistance offered by the web. To ensure the proper maintenance of this layer or cushion the web, after it is freed from the roll is preferably led close to the roll for a ways to offer a resistance close to the roll between 100 which and the web the layer forms. While this may be done in various ways, as shown, the paper roll 6 is employed for the purpose, being located in close to the couch roll, so as to hold the web in close to the couch roll 105 and prevent the dispersion of the air without the formation of the layer or cushion from which the felt draws the web.

In the operation of the device the valve 47 is opened to admit air under pressure 110 through the first passage 29 shown at the left hand end of the roll in Fig. 6. This air acts to free the "tail" of the web, which is a narrow strip separated from the main web body, and which is first led over to the 115 felts at the start of operations. This "tail" is freed from the wire and supported on the air layer or cushion and draws off this layer or cushion by the felt, and the web is thus started to the press rolls. As the operation 120 proceeds and the full width of the web is to be taken off the wire, the controlling lever 39 is operated to open the other passages for the admission of air to loosen and free the 125 web gradually the entire width and sup- 130

port it on the air layer or cushion from which it is drawn off by the felt, or other web taking devices.

With this construction the web is removed from the wire throughout its width and the air acts to form a layer or cushion which supports the web at the point where it is removed and the felt draws the web from off this air cushion. The resistance offered to the drawing of the web is therefore very greatly reduced and danger of breakage to a very large extent is overcome, particularly when operating at high speeds or with thin webs.

15 While the invention has been shown and described in its preferred forms, it will be understood that various arrangements may be provided for producing this air cushion and that the invention is not to be limited 20 to the particular valve construction and arrangement shown and described.

What is claimed is:

1. In a paper making machine, the combination with a couch roll and the wire, of 25 means for producing a fluid pressure under the web throughout its width to remove the web from the wire and to yieldingly support it, means for controlling the fluid pressure at various points throughout the width 30 of the web, and web taking devices for drawing away the web thus supported.

2. In a paper making machine, the combination with a couch roll and the wire, of 35 means for producing an air pressure under the web throughout its width to remove the web from the wire and to yieldingly support it, means for controlling the air pressure at various points throughout the width 40 of the web, and web taking devices for drawing away the web thus supported.

3. In a paper making machine, the combination with a couch roll and the wire, of 45 means for producing an air current, a plurality of valves for controlling the air, connections from the valves extending widthwise under the web, and means for adjusting the valves independently of each other.

4. In a paper making machine, the combination with a couch roll and the wire, of 50 means for producing an air current, a plurality of valves for controlling the air, connections therefrom extending widthwise under the web, means for adjusting the valves independently of each other, and means for controlling the air admitted through a number 55 of the valves simultaneously.

5. In a paper making machine, the combination with a couch roll and the wire, of 60 a pressure chamber, means for supplying air under pressure thereto, a plurality of valves in the chamber, passages from the valves opening at various points widthwise under the web, means for independently adjusting the valves, and means for control-

ling the air admitted through a number of 65 the valves simultaneously.

6. In a paper making machine, the combination with a perforated couch roll and the wire, of means for passing air under pressure through the roll under the web to 70 remove the web from the wire throughout its width and to form a layer of air under the web to support it, means for controlling the air pressure widthwise of the web, and web taking devices drawing the web off the 75 layer of air.

7. In a paper making machine, the combination with a perforated couch roll and the wire, of means for passing fluid under pressure through the roll under the web 80 to remove the web from the wire throughout its width and to form a fluid layer under the web to support it, means for controlling the fluid pressure widthwise of the web, and web taking devices drawing the web off the fluid 85 layer.

8. In a paper making machine, the combination with a perforated couch roll and the wire, of a pressure chamber, passages extending from the chamber within the roll 90 and opening at different points widthwise thereof, adjustable valves controlling the passage, and a main valve common to and controlling the admission of pressure fluid through certain of the adjustable valves. 95

9. In a paper making machine, the combination with a perforated couch roll and the wire, of a pressure chamber, passages extending from the chamber within the roll and opening at different points widthwise 100 thereof, a stationary valve plate, adjustable valves co-operating with the plate to control pressure to the passages, and a movable main valve plate common to the valves for simultaneously controlling the passage of 105 pressure fluid through certain of the adjustable valves.

10. In a paper making machine, the combination of a couch roll and the wire, of 110 passages opening along the roll at different points widthwise thereof, an adjustable valve for each passage to control admission of pressure fluid thereto, and a main valve controlling the admission of fluid simultaneously through all the adjustable valves. 115

11. In a paper making machine, the combination of a couch roll and the wire, of 120 passages of different lengths opening along the roll, an adjustable valve for each passage, and a main valve controlling the admission of pressure fluid simultaneously through the adjustable valves.

12. In a paper making machine, the combination with a couch roll and the wire, of 125 air pressure means acting to remove the web from the wire throughout the width of the web, means for holding the web close to the couch roll after its removal to form

an air layer between the web and the roll for holding the web close to the couch roll 10 on which the freed web floats, and web after its removal to form an air layer between the couch roll and the web on which taking devices for drawing the web from the freed web floats, and web taking devices off this layer.

13. In a paper making machine, the combination of a couch roll and the wire, of air pressure means acting to remove the web from the wire throughout the width of the web, a roll located adjacent the couch roll 15 for drawing the web from off this layer.

In testimony whereof, I have hereunto set my hand.

FRANK W. MONAGHAN.
